UNITED STATES PATENT OFFICE

THEODORE BOSSARD, OF SALT LAKE CITY, UTAH, ASSIGNOR TO THE NATIONAL PRODUCTS, INCORPORATED, OF SALT LAKE CITY, UTAH, A CORPORATION OF UTAH

VACUUM TANK

Application filed November 7, 1927. Serial No. 231,493.

My invention relates to vacuum tanks, and has for its object to provide a new and efficient vacuum tank for use in drawing the gasoline from the tank to the carburetor of an automobile.

A further object is to provide a highly efficient vacuum tank which will be made of very few working parts, thereby making it economical to construct and quickly assembled 10 with very little time taken to assemble the tanks.

A still further object is to provide a tank which will be more efficient than has heretofore been accomplished and one which will 15 continue to operate under all conditions of weather, engine conditions and continued pull of the engine so that the tank will store sufficient gas in the reserve tank that the engine will never run out of fuel.

20 These objects I accomplish with the device illustrated in the accompanying drawings, in which similar numerals and letters of reference indicate like parts throughout the several views and as described in the specification 25 forming a part of this application and pointed out in the appended claims.

In the drawings, in which I have shown the best and most preferred manner of building my invention, Figure 1 is a section diametrically through both the suction tank and the 30 reserve tank, with parts shown in elevation. Figure 2 is a section of the suction tank. Figure 3 is an enlarged view of the double valve. Figure 4 is a plan view of the valve shifting 35 arms. Figure 5 is a plan view of the main control arm connecting the float with the top of the tank.

In the drawings I have shown the reserve outer tank as A, and the inner suction tank as 40 B, with a cover C covering both tanks. The said cover C is provided with two spaced apart bosses 1 and 2 thereon, with the said boss 1 centrally bored at 4 to receive a pipe connection from the supply tank of the automobile, and having said bore running through the entire boss. Part of the said boss 1 is formed 45 on the under side of the cover and is shown as 3, Figures 1 and 2. The said bore 4, through the boss 1 and 3, is internally threaded on the top end and the lower end is sloped 50

outwardly to direct all the incoming gas upon the side wall of the suction tank B. The said boss 2 has a square member 5 formed on the under side thereof of the cover and a pair of bearing arms 6 and 7 are formed on the under and outer edge thereof. The said boss 2 is centrally bored and threaded to receive a suction pipe from the intake manifold of the automobile, and a smaller bore 8 is provided, running down into the member 5, with a 55 transverse bore 9 connecting with said bore 8 and with a bore 10, which bore 10 is parallel with the bore 8. The upper end of the said bore 10 is formed into a valve seat 11. A centrally bored plug 12 is screwed into the 60 top side of said cover C near the boss 2, and the lower end of said plug forms a valve seat 13. A valve stem 14 is provided in a transverse cut 15 in the said member 5, and has both ends 16 and 17 tapered and formed into 65 valves with guide stems 18 and 19 formed on the extreme ends thereof. The said stem 18 fits into the said bore through the said valve seat 13 and the said stem 19 fits into the valve seat 11 so that the stem 14 is kept in alignment with the two spaced apart valve seats 11 and 13 and so that the valves 16 and 17 will at 70 all times be in alignment with their respective seats 13 and 11. A cross bar 20 is provided through said stem 14, by which said stem and 75 valves are operated, opening one valve and closing the opposite one. The said valves 11 and 13 are in alignment with each other, as shown in Figures 1 and 2. Valve shifting arms 21 and 22 are secured pivotally to the 80 said member 5 by the pivot pin 23 and have their outer ends spaced apart by the spacer member 24. The said arms 21 and 22 are alike and each has a cut 25 in the top side thereof in which the said cross bar 20 is carried and by 85 which it is operated for, as the arms 21 and 22 are moved, the slot moves the bar 20, thereby moving the valves. Between the ends of the arms 6 and 7 a control lever 27 is mounted on the pivot pin 28. The said arm is bifurcated 90 and transversely bored on its outer end to receive the float connection 29, which connects the said control lever 27 with a float F. The said lever 27 is slotted vertically therethrough, as at 30, and is transversely bored to receive 95 100

the pivot pin 31. An arm 32 is carried on the said pin 31 and said arm is bored at 33 to receive one end of a spring 34. From there the arm is formed in the approximate shape of a 5 Figure L, with the outer and upper end thereof widened, as at 35, and with the inner face 36 sloping in and the face 37 sloping upwardly and inwardly. The said faces 36 and 37 are adapted to fit against the said spacer 24 by 10 the pressure of the spring 34 which spring holds the faces 36 and 37 against the said spacer at all times, and when the float rises or falls the faces 36 and 37 act upon the spacer 24 and move the arms 21 and 22, thereby actuating the valves. Stop lugs 39 and 40 are provided on the said arms 6 and 7 to limit the movement of the control arm 27.

The bottom end of the said suction tank is provided with an outlet pipe 41, having a 20 bend 42 therein which makes the outlet of the end of the pipe parallel with the end of the tank B. The end of the said pipe 41 has a ring groove 43 cut therearound and a cover cap 44 is provided with four spaced apart arms 45, 25 having the ends thereof bent inwardly, adapted to engage with said groove and to hold the cover cap 44 spaced from the end of the said pipe 41. A flat, circular piece of metal 46 is provided within the space between the cover cap 44 and the end of the pipe 41 to act as a closure valve therefor. The tank A is provided with the usual outlet control valve V in the bottom side thereof.

The operation of my invention is as follows:—

The engine of the automobile is rotated and, as the pistons draw the fuel into the gas chamber by the suction created thereby, the suction in the intake manifold draws the air 40 out of the suction tank B and draws gasoline from the supply tank through the connection therewith and through the boss 1 into the tank. The gas entering the boss 1 will be thrown against the side of the tank by the 45 slope of the hole 4. When the incoming gas has raised the float F to the full position, the control lever arm 27 is raised, which, in turn, raises the arm 32, and the action of the faces 36 and 37 moves the valve shifting arms 21 and 22 by contact with the spacer 24 and the valve stem 14 is moved downwardly by the action of the face 37 and the intake valve 11 is closed and the air intake valve 13 is opened, allowing air to enter the tank 50 B. When air is allowed to enter said tank the gasoline will flow down through the pipe 41 and will press the valve 46 upwardly against the cap 44, allowing the gasoline to pass from the tank B into the tank A and 55 from there into the engine carburetor as used. When the gasoline has been drawn from the tank B so that the float F is down, the control arm 27 is drawn down with the float and when the arm 27 is down the arm 32 passes 60 down over the spacer 34 so that the face 36

presses the spacer and the arms 21 and 22 upwardly. This reverses the movement of the valve stem 14 and opens the intake suction valve 11 and closes the air valve 13 so that no more gasoline can be drawn from the tank 70 C and starts the suction from the intake manifold drawing gasoline into the tank C from the supply tank. This suction also closes the valve 46 in the pipe 41 so that no more gas can flow from the tank C until the suction is 75 stopped. When the tank C is again full to the predetermined level the action of the levers and valve stem reverses the said stem, again closing the suction valve and opening the air valve. This operation is continued as long as 80 gasoline is being used from the tank A and the suction tank C.

Having thus described my invention I desire to secure by Letters Patent and claim:—

1. In a vacuum tank the combination of a 85 reserve tank; a suction tank mounted within said reserve tank; a cover for both of said tanks, having intake and suction connections; an air intake provided in said cover operated by a valve; a valve stem mounted so that one 90 end is within the air intake valve and the other end is within the suction intake connection; valves formed on the ends of said valve stem to open and close said intake valve and said suction connection; support arms 95 formed on the bottom side of said cover; a control lever mounted between said arms; a float carried within said suction tank and connected with said control lever; another arm 100 pivoted to said control lever, having its inner faces at diverging angles to each other; a spring to control the action of said last mentioned arm; two spaced apart arms, having slots cut in the upper side thereof, and a spacer between the two outer ends thereof, 105 pivoted on the lower side of said cover, with said spacer adapted to be in constant contact with either of the diverging faces of said arm; a cross bar through said valve stem adapted to fit into the slots in said spaced 110 apart arms to be actuated by said arms to open and close the intake suction and air valves as necessary, substantially as described.

2. In a vacuum tank the combination of a 115 reserve tank; a suction tank mounted within said reserve tank; a cover for both of said tanks, having intake and suction connections therein; an air inlet in said cover; a valve stem mounted so that one end thereof is carried in the air inlet and the other end in the 120 suction intake openings; valves formed on the said stem to control the air intake and the suction intake openings; a lever mounted between suitable bearing arms on the under side of said cover; a float carried on the free 125 end of said lever; a spring held arm pivoted to said lever between the float and the lever mounting; an angled face formed on one side of said spring held arm; a roller spacer, carried between two spaced apart slotted arms, 130

adapted to be actuated by the movement of said angled face when the float raises and lowers in the tank; and a cross bar through said valve stem to fit into said slotted arms to actuate the valves by the movement of the float.

3. In a vacuum tank the combination of a cover therefor having suitable spaced apart bearing arms on the lower face thereof, and provided with air, suction and gasolene openings therein; a valve stem having the ends thereof carried in the air and suction openings, with the valves formed thereon adapted to close one or the other of said openings at all times; a lever mounted between said bearing arms having the free end secured to a float; a spring held angled arm pivoted to said lever; two spaced apart slotted arms mounted with a spacer roller between their free ends with said roller adapted to contact with one or the other of the angled faces of said angled arm to actuate the arms by the movement thereof; and a cross bar carried in said valve stem adapted to actuate the stem when the spaced apart arms are actuated.

In testimony whereof I have affixed my signature.

THEODORE BOSSARD.
